UNITED STATES PATENT OFFICE.

CHARLES A. E. RUEBEL, OF CHILlicothe, OHIO.

ELECTRICAL BURGLAR-ALARM.

SPECIFICATION forming part of Letters Patent No. 267,987, dated November 21, 1882.

Application filed September 19, 1882. (No model.)

To all whom it may concern:

Be it known that I, CHARLES A. E. RUEBEL, an alien and a native of Germany, residing at Chillicothe, in the county of Ross and State of Ohio, have invented certain new and useful Improvements in Electric Burglar-Alarms; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

This invention relates to certain new and useful improvements in burglar-alarms, and it belongs to that class in which a spring-motor is employed to sound the alarm, which spring-motor is released by a movement of the armature when the current of electricity is broken; and it consists in the combination and construction of the parts, as will be hereinafter set forth, and pointed out in the claim.

In the annexed drawings, Figure 1 is a side view, showing the circuit-breaker connected with the window. Fig. 2 is a view showing the arrangement of the magnet, armature, and spring-motor for sounding the alarm. Figs. 3 and 4 are detached views of the circuit-breaker; 30 and Fig. 5 is a detail view, showing the construction and relative positions of the armature and bell-hammer.

In the annexed drawings, A represents the circuit-breaker, the normal position of which, 35 when attached to a closed window or the door of a safe or other object, is closed so as to complete the circuit. This circuit-breaker consists of two plates of non-conducting material—leather or rubber answering well—which plates 40 are attached to each other by stitches, and are provided with contact-points to which wires are attached. One of the connecting-points may be said to consist of an anvil, b, which is let into the upper plate. The other point, a, 45 consists of a flat plate of spring metal, one end of which is free and is located over the anvil b. The other end is secured between the plates, and has attached to its end a connecting-wire. The wires which are attached to this circuit- 50 breaker are preferably insulated. The circuit-

breaker, when the apparatus is in use, is placed in the jamb of the window or door or between the movable portions of any object to be guarded, so that the points of the circuit-breaker will be in contact and a closed circuit 55 will result. One of the wires attached to the hereinbefore-described circuit-breaker leads to one pole of the battery and the other one is attached to the binding-post c on the outer side of the receptacle which incloses the electro-magnet and the alarm mechanism. The wire from the other pole of the battery is connected to the binding-post d, located adjacent to the post c. These binding-posts c and d are connected to the electro-magnets B B by the terminal wires of their coils. It is evident that by this arrangement a current is always passing from the battery to the magnet. It is also evident to those skilled in the arrangement of electrical instruments that ground-wires may 60 be used, and, indeed, it is preferable where the alarm-instrument is located at a considerable distance from the object to be protected.

The alarm mechanism and the means for releasing the same are inclosed within a suitable 75 box, which is provided with an opening through which passes a stem for winding up the alarm mechanism, and openings through which the hammer for sounding the bell passes. The box is also provided with means for attaching the 80 same to a wall, and it is preferably composed of non-conducting material. Attached to one of the perpendicular sides of the box is one or more electro-magnets, B B, having an armature, C, which is pivoted within a bracket attached to the box, so as to move to and from the cores of the magnets. This armature C is provided at its end with a binding-post, D, or its equivalent, through which passes the rod e, which has attached at one end a spring, f, 90 which has sufficient strength to draw the armature away from the magnet and overcome any residual magnetism which may remain in the cores after the circuit is broken. The armature C moves between guides F, which project over the same. This armature C is provided at its free end with a catch, E, which is attached to the same by means of the lower end of the post D, which passes through the 95 parts and unites them to each other. This 100

catch E holds or retains the bell-hammer H when the circuit is closed, as will be hereinafter set forth.

The mechanism for actuating the bell-hammer consists of an ordinary train of gear-wheels which are actuated by a spring which is provided with a shaft which extends through the casing for the purpose of winding the same. The actuating mechanism is provided with an escapement-wheel, i, above which is located a shaft carrying a detent, k, and a lever, H, to which is attached the bell-hammer. The lever H, as shown in Fig. 5, is arranged so that the catch of the armature C will strike against the same and prevent it vibrating or sounding an alarm when the circuit is closed. The end of the lever H passes through the casing and strikes upon a bell or gong, as shown.

The operation of this invention from the foregoing description may be readily understood; and among its advantages over similar apparatus, aside from its construction, may be stated that it is arranged so as to operate upon a closed circuit, and any break in the circuit caused either by the door, window, &c.,

being opened, or cutting wires immediately sounds an alarm which will continue until the window is closed or the alarm mechanism runs down.

Having described my invention, what I claim as new, and desire to secure by Letters Patent, is—

In a burglar-alarm which is adapted to operate in a closed circuit so as to sound an alarm when the circuit is broken, the combination of the electro-magnets B B, armature C, guide-rod F, catch E, attached to the end of the armature by the post D, with retracting-spring f, the spring-motor with vibrating bell-sounding lever H, bent so as to engage with the catch E, the parts being arranged and organized substantially as described, and for the purpose set forth.

In testimony whereof I affix my signature in presence of two witnesses.

CHARLES A. E. RUEBEL.
